UNITED STATES PATENT OFFICE.

ELMER HARROLD AND CLINTON G. WILDERSON, OF LEETONIA, OHIO, ASSIGNEES TO
THE CRESCENT MACHINE COMPANY, OF LEETONIA, OHIO, A CORPORATION OF OHIO.

SAW-GUARD.

1,050,649.

Specification of Letters Patent. Patented Jan. 14, 1913.

Application filed May 28, 1910. Serial No. 564,014.

To all whom it may concern:

Be it known that we, ELMER HARROLD and CLINTON G. WILDERSON, both of Leetonia, Columbiana county, Ohio, have invented a new and useful Improvement in Saw-Guards, of which the following is a full, clear, and exact description, reference being had to the accompanying drawings, forming part of this specification, in which—
10 Figure 1 is a side view illustrating the application of our invention to a saw; Fig. 2 is a front view; Fig. 3 is a detail view showing the connection between the shoe supporting member and the supporting arm therefor; and Fig. 4 is a detail view of the connection between the shoe and the supporting member therefor.

Our invention has relation to saw guards, and is designed to provide a simple, convenient, and efficient form of guard which can be readily attached to various forms of saw tables, either fixed or tilting; and which, when applied to a tilting table will not interfere with the operation of such table. Also to provide a guard which will completely cover the saw and prevent the possibility of getting the hands or any part of the body in contact therewith, and which will also prevent strips of wood being thrown by getting on to the saw.

A still further object is to provide a shoe of this kind which is readily adjustable as far forward or backward on the table as may be desired; and which can be swung backwardly entirely out of the way when not desired for use.

The nature of our invention will be best understood by reference to the accompanying drawings, in which we have shown a preferred embodiment thereof, and which will now be described, it being premised, however, that various changes can be made in the details of construction and arrangement of the parts by those skilled in the art without departing from the spirit and scope of our invention as defined in the appended claims.

In these drawings, the numeral 2 designates a saw table, and 3 a saw.

4 is a shoe, which is preferably made of wood, although not necessarily, and which is formed with a vertical, longitudinal slot 4^a. This shoe is closed at the top, and fits over the saw in the manner shown in Figs. 1 and 2, completely covering the same.

Rigidly secured to one side of the shoe is a metal flange or plate 5, which is provided with a central bolt or pin hole, and with two projecting lugs 6.

7 is a hub member, which is provided with an eye portion which loosely fits a pin or bolt 8 inserted therethrough and into the member 5, and which is also provided with a sleeve or socket portion 9 to fit the end of a supporting bar or arm 10. The hub member is also provided with a lug 7^a, which extends between the two lugs 6 to limit the pivotal movement of the shoe with reference to the hub member. The bar or arm 10 is adjustably secured at its upper rear end portion in a hub member 11, which is pivotally supported on the end portion of an overhanging goose-neck bar or rod 12. This bar or rod is secured at its lower end in a bracket 13, which is rigidly secured to the frame of the machine. The hub member 11 is provided with a stop lug 11^a, which is arranged to engage the projecting stop lug 11^b of a collar 11^c secured to the arm 12, when the bar 10 and shoe 4 are swung upwardly and backwardly out of use, into the position shown in dotted lines in Fig. 1.

The operation of the device will be apparent. The shoe 4 completely covers the saw, but will readily move upwardly to permit the passage thereunder of the piece being sawed, by reason of its pivotal engagement with the pin or bolt 8. The front end of the shoe is undercut or beveled backwardly, as shown at 4^b, so that as the piece to be sawed is shoved underneath the same, the front end of the shoe will first rise slightly, and then the whole shoe will lift by parallel movement. The pivotal connection on the pin or bolt 8 gives sufficient flexibility to the shoe, while the provision of the stop lugs 6 prevents undue movement of the shoe.

When it is not desired to use the guard, it may be thrown upwardly and backwardly into the position shown in dotted lines in Fig. 1, the stop lug 11^a engaging the stop lug 11^b of the collar 11^c to hold the shoe in this position. By loosening the set screw which secures the upper end portion of the member 10 in the hub member 11, it will be obvious that the shoe may be adjusted as far forwardly or backwardly of the table as may be desired. This is a feature of special importance in connection with saws em-

ploying two mandrels, each carrying a saw, and so arranged that either saw can be brought up into working position.

It will be obvious that the details of the device may be changed in many particulars without departing from our invention. Thus, the form of the supporting bar or arm 12 and the exact means of attaching it to the frame of the saw may be varied to suit the particular form of saw table to which the device is to be applied. Changes may also be made in the details of the connections between the shoe and its support.

What we claim is:—

- 15 1. A saw guard comprising a frame in back of the saw, a shoe adapted to fit over the saw and rest on the saw table, a support pivoted to the frame and to the shoe, the pivotal connections being such that the shoe will first swing on its connection with the support when the work piece is moved into engagement with the saw and then swing back to its normal position with relation to the support while the support will swing on its pivotal connection with the frame, substantially as described.
- 20 2. A saw guard comprising a support at the back of the saw, a shoe adapted to fit over the saw and to lie parallel with the upper portion of the saw table before the work piece is inserted and after one end of the work piece has passed beyond the saw, a support pivoted to the shoe and the frame, the pivotal connections being such that the shoe will first be swung at an angle when the work piece engages the saw and then swing into a position which is parallel with the

saw table after the end of the work piece has passed the center of gravity of the shoe, substantially as described.

40

3. A saw guard comprising a supporting frame in back of the saw, a shoe adapted to fit over the exposed portion of the saw above the table, pivotal connections between the frame and the shoe, and a cam on the front end of the shoe arranged to be engaged by the work piece to raise the shoe, the pivotal connections being such that the front portion of the shoe will be raised when engaged by the work piece and then the heel portion thereof after the work piece has passed the center of gravity of the shoe, substantially as described.

45

4. A saw guard comprising a vertically slotted shoe adapted to fit over the exposed portion of the saw, a member secured thereto and carrying a pin or pivot, a hub member engaging said pin or pivot, said hub member and the first named member having coöperating stop lugs, a supporting arm to which the hub member is secured, an overhanging support, a sleeve member loosely mounted thereon and having means for adjustably securing thereto the upper end portion of said supporting arm, and means for limiting the pivotal movement of the arm; substantially as described.

50

In testimony whereof, we have hereunto set our hands.

ELMER HARROLD.

CLINTON G. WILDERSON.
